ATTORNEY

UNITED STATES PATENT OFFICE.

NICHOLAS J. ENGLER, OF IPSWICH, DAKOTA TERRITORY.

STOVE.

SPECIFICATION forming part of Letters Patent No. 406,204, dated July 2, 1889.

Application filed February 28, 1889. Serial No. 301,499. (No model.)

To all whom it may concern:

Be it known that I, NICHOLAS J. ENGLER, of Ipswich, in the county of Edmunds and Territory of Dakota, have invented a new and Improved Stove, of which the following is a full, clear, and exact description.

The invention relates to stoves for burning hay, straw, or other light fuel; and its object is to provide a new and improved stove which is simple and durable in construction, very effective in operation, and prevents the smoking and puffing out of fire into the room, which so frequently occurs at certain intervals in stoves of this class that are now in use.

The invention consists of certain parts and details and combinations of the same, as will be hereinafter described, and then pointed out in the claims.

Reference is to be had to the accompanying drawings, forming a part of this specification, in which similar letters of reference indicate corresponding parts in all the figures.

Figure 1 is a sectional side elevation of the improvement. Fig. 2 is a sectional plan view of the shell on the line $x-x$ of Fig. 1, and Fig. 3 is an inverted plan view of the shell-bottom.

The improved stove is provided with a cylindrical shell A, preferably made of sheet metal, and rests at its lower end on a suitably-constructed base B. Inside of the cylindrical shell A, near its bottom, is suspended on lugs A' an inverted-cone-shaped bottom C, having its apex a short distance above the base B, as is plainly shown in Fig. 1. The shell A, below the top edge of the cone-shaped bottom C, is provided with a number of apertures D, through which air is admitted and heat allowed to escape, whereby the lower portion 40 of the stove is prevented from being overheated.

On the outside of the cylindrical shell A are secured suitable handles E for moving the shell about when filling or emptying it, and the upper end of the shell is closed by a cover F, secured air-tight to the shell, forming part of the same. From the shell A, directly above the upper edge of the bottom C, leads a stove-pipe G, which passes into a heater or cooking-stove H, of any approved construction, and used for cooking, baking, or other purposes.

In the rear end of the heater or cooking-

stove H is arranged a transverse partition H', containing an aperture H², adapted to be opened or closed by a damper H³, held to slide transversely on the partition H', and manipulated by suitable means from the outside. The aperture H² is preferably located directly opposite the stove-pipe G, and it opens into a chamber H⁴, formed at the rear end of the heater or stove H, and connected at its top with the usual chimney-pipe H⁵, provided with a damper I.

Inside of the shell A are arranged one, two, or more pipes J, extending vertically, open at their lower ends, and each provided with a number of apertures K, leading to the interior of the shell A. The upper ends of the pipes J connect with the horizontally-extending pipe L, also provided with apertures. 70 Into one of the pipes J or the pipe L leads a short pipe J², formed in the shell A, and connected by a pipe N with the chimney-pipe H⁵ above the damper I, as is plainly shown in Fig. 1. 75

The usual dampers O are located in the shell A directly above the upper edge of the bottom C and below the lower ends of the pipes J, as shown in Fig. 1. On the under side of the cone-shaped bottom C are arranged convenient handles C', for placing the bottom in the shell or removing it from the same.

The operation is as follows: The shell A is filled, in the usual manner, with straw or hay 85 from the bottom when the cone-shaped bottom C is removed. As soon as the shell A is filled the bottom C is replaced, and the shell with its contents is set on the base B, the pipe G projecting into the stove or heater H, 90 and the pipe N connecting the pipes J and L with the chimney-pipe H⁵. The straw, hay, or other light fuel in the shell A is now ignited, and the heat and smoke arising from the burning fuel pass through the pipe G 95 into the heater or stove H. The latter is then heated and may be utilized for cooking or baking purposes in the usual manner.

The smoke and gases from the heater H can pass through the aperture H² into the 100 chamber H⁴, and from the latter through the chimney-pipe H⁵ to the outside. The steam or vapor generated from the fuel inside of the shell A passes into the pipes J, J', and L,

through the pipe J² into the pipe N, and from the latter into the chimney-pipe H³. As the steam or vapor of the fuel is drawn off in the manner above described, the cause of smoking and puffing out of fire into the room is removed, and consequently the fuel burns very evenly on the cone-shaped bottom C in the shell A.

Having thus fully described my invention, 10 I claim as new and desire to secure by Letters Patent—

1. In a stove of the class described, the combination, with a shell having a cone-shaped bottom and a smoke-pipe leading from the said bottom, of perforated pipes held in the said shell and connecting with the chimney-pipe, substantially as shown and described. 15

2. In a stove of the class described, the combination, with a shell provided with a heater 20 or cooking-stove having a chimney-pipe, and also provided with a cone-shaped bottom, of a smoke-pipe leading from the said shell above the said bottom into the heater or cooking-stove, and perforated pipes held in the 25 said shell and connecting with the chimney-pipe of the said heater or stove, substantially as shown and described.

3. In a stove of the class described, the combination, with a heater or cooking-stove provided with a chimney-pipe, a base, and a shell 30 resting on the said base and provided near its bottom with apertures, of a cone-shaped bottom suspended in the said shell above the said apertures, a smoke-pipe leading from the said shell above the said cone-shaped bottom into the heater or cooking-stove, and perforated 35 pipes held in the said shell and connected with the chimney-pipe of the heater or cooking-stove at their upper ends, substantially as 40 shown and described.

4. In a stove of the class described, the combination, with a heater or cooking-stove provided with a chimney-pipe, a base, and a shell 45 resting on the said base and provided near its bottom with apertures, of a cone-shaped bottom suspended in the said shell above the said

apertures, a smoke-pipe leading from the said shell above the said cone-shaped bottom into the heater or cooking-stove, perforated pipes held in the said shell and connected at their 50 upper ends with the chimney-pipe of the heater or cooking-stove, and dampers held on the said shell above the said cone-shaped bottom, substantially as shown and described.

5. In a stove of the class described, a heater 55 or cooking-stove provided with a transverse partition having an aperture, a damper held in the said transverse partition to open or close said aperture, and a chimney-pipe held on the said heater or cooking-stove and into 60 which discharges said opening, in combination with a base held in front of the said heater, a shell closed at the top and resting with its open bottom on the said base, a cone-shaped bottom suspended in the lower end of the said 65 shell, a smoke-pipe leading from the said shell above the said bottom into the said heater, and perforated pipes extending vertically in the said shell connected with said chimney-pipe, substantially as shown and described. 70

6. In a stove of the class described, a heater 75 or cooking-stove provided with a transverse partition having an aperture, a damper held in the said transverse partition to open or close said aperture, and a chimney-pipe held on the said heater or cooking-stove and into 80 which discharges said aperture, in combination with a base held in front of the said heater, a shell closed at the top and resting with the open bottom on the said base, a cone-shaped bottom suspended in the lower end of the said shell, a smoke-pipe leading from the said shell above the said bottom into the said heater, perforated pipes extending vertically in the said shell connected with said chimney- 85 pipe, and dampers held in the said shell above the said bottom, substantially as shown and described.
